UNITED STATES PATENT OFFICE.

JOHN DEAN, OF RACINE, WISCONSIN.

TOILET ARTICLE.

1,182,991.

Specification of Letters Patent.

Patented May 16, 1916.

Application filed May 14, 1914. Serial No. 838,577.

To all whom it may concern:

Be it known that I, JOHN DEAN, a citizen of the United States, residing at Racine, in the county of Racine and State of Wisconsin, have invented certain new and useful Improvements in Toilet Articles, of which the following is a specification.

This invention relates to certain improvements in toilet articles, and more particularly relates to bottles or receptacles for dispensing powdered soap and the like; and the objects and nature of the invention will be readily understood by those skilled in the art in the light of the following explanation of the accompanying drawings illustrating what I now believe to be the preferred embodiment or mechanical expression of my invention from among other formations within the spirit and scope 20 thereof.

The object of the invention is to provide a soap powder dispensing bottle or shaker with a removable closure normally locked or secured thereto and closing the powder egress 25 opening therefrom and carrying and forming the base of a brush or other face rubber for receiving soap powder from said shaker when the closure is detached therefrom, and for rubbing the face to form lather thereon 30 for shaving purposes when said closure is secured on the shaker so that the shaker forms the handle of said rubber, whereby the soap powder shaker and the face rubber form and constitute a single toilet article 35 for shaving purposes, and the shaker can be thrown away when emptied and a filled shaker substituted therefor, and whereby the shaker when made of transparent material, such as glass, will enable 40 a person to see the quantity of powder therein and will thus serve to warn the owner when the supply in the shaker being used is about exhausted.

The invention consists in certain novel 45 features in a combination of parts as more fully and particularly set forth and specified hereinafter.

Referring to the accompanying drawings;—Figure 1, is a perspective view of a 50 toilet article involving my invention. Fig. 2, is a longitudinal section. Fig. 3, is a perspective illustrating the manner of using the same in applying the powder to the rubber.

55 In the drawings, I show a glass, or other transparent-material, soap-powder-contain-

ing bottle 1, having its lower end or bottom formed to constitute a base on which the bottle can stand in an upright position. The open end or mouth of this bottle contains 60 a slip, friction, or plug stopper, cap or disk 2, fitted down within the mouth of the bottle and this stopper is formed to permit egress of the soap powder when the bottle is reversed and shaken. For instance I show 65 this stopper formed with the powder egress opening 3. The neck of the particular bottle that I have selected for illustrative purposes, is formed with exterior screw threads 4, whereby the outside or cover-all closure 5, is secured or locked to the bottle to cover the mouth thereof and its stopper 2, and thereby close the egress opening 3. This closure 5, is formed rigid with a top 70 socket 6, in which a suitable rubber is secured. For instance, I show hairs or bristles fixed in said socket to form shaving brush 7, projecting from the closure in longitudinal continuation thereof and of the bottle when the closure is thereon. The 80 closure 5, in the example illustrated, is in the form of a flanged imperforate cap having its flange threaded or otherwise formed to mesh with the exterior thread of bottle neck and screw thereon to cover the mouth and neck of the bottle and tightly close the same against the passage of water from the shaving brush into the interior of the bottle or onto the top surface of the interior stopper of the bottle. It is essential to prevent 85 water or moisture dripping or flowing from the brush into the bottle particularly as the article is often left in an upright position standing on the base of the shaving brush-handle-forming bottle or shaker. 90

According to my invention, soap powder bottles shaped to form and constitute shaving brush handles and loaded with soap powder, can be placed on the market and sold separately as soap powder shakers, or other bottles, cans or receptacles of soap powder, and if so desired, each can be fitted with a removable closure provided with and forming the base of a lather forming face rubber, such as a shaving brush. 100

In using this toilet article for shaving purposes, the closure will be removed and the brush moistened to the desired degree. The brush can then be held in the left hand, for instance, while the powder shaker is held in the right hand and manipulated to discharge the desired quantity of powder on 110

the wet brush. The closure will then be restored to its normal position on and sealing the shaker or bottle, which then constitutes the handle by which the brush is manipulated in working the soap into lather on the face preparatory to shaving.

Where the soap powder bottles are formed of glass or other transparent material through which the powder can be readily seen, as I prefer, the user can always observe without effort, the quantity of powder in the bottle and will be thereby reminded to secure a fresh or filled bottle when the bottle being used as a part of the brush is about 10 emptied. I intend to place filled bottles on the market without the brush carrying closure, so that users can purchase such filled bottles and apply the same to the closures carrying the brushes when powder in the 15 bottles being used is exhausted and such emptied bottles are thrown away.

Although I have specifically described a particular bottle, yet I do not wish to so limit my invention, nor do I wish to limit 20 my invention to any particular kind of brush-carrying closure for said bottle inasmuch as I can employ other closures than those of the screw cap type, that I happen to disclose hereby.

30 It is evident that various modifications and variations might be resorted to without departing from the spirit and scope of my invention and hence I do not wish to limit myself to the exact disclosure hereof.

35 What I claim is:—

1. A toilet article for shaving purposes consisting essentially of a shaving brush provided with a removable handle formed by a soap powder shaker having a transparent wall, said brush also provided with a

base constituting a water-shedding closure for and removably receiving the outlet end of said shaker.

2. As a new article of manufacture, a 45 shaving brush composed of a soap powder shaker forming the brush handle, and the soap applying and rubbing body having a base in the form of a closure for and removably receiving the outlet end of the shaker and constituting means by which said 50 body can be held when the shaker is detached and being employed to sprinkle powder on said body, substantially as described.

3. A lather-forming toilet article consisting essentially of a soap-receiving and face-rubbing element, a holder depending from and permanently receiving said element and forming a water-shedding closure cap, and a base-forming handle consisting of a powdered soap shaker having its upper outlet end formed to be covered by said cap and to be thereby removably secured to said element in handle-forming position with respect thereto, substantially as described. 55

4. A shaving brush provided with a sectional handle embodying a permanent bristle-carrying section depending in the form of a water-shedding closure cap adapted to close the upper outlet end of a soap powder bottle 70 and thereby removably couple the bottle to said section to constitute a base-forming handle for the shaving brush, substantially as described.

In testimony whereof I affix my signature 75 in presence of two witnesses.

JOHN DEAN.
